[57] CLAIM

The ornamental design for a plate-like pallet, as shown and described.

DESCRIPTION

FIG. 1 is a perspective view of a pallet showing my new design;

FIG. 2 is a top plan view thereof;

FIG. 3 is a bottom plan view thereof;

FIG. 4 is a side elevation view thereof, the opposite side being a mirror image of that shown;

FIG. 5 is an end elevation view thereof, the opposite end being a mirror image of that shown.

FIG-1

FIG-2

FIG-4

FIG-3

FIG-5
